W. S. STEVENSON

BUTT WELDING PIPE

Filed Oct. 10, 1923

FIG. 1.

FIG. 2.

Inventor
Winfield S. Stevenson

By C. C. Shepherd.

Attorney

UNITED STATES PATENT OFFICE.

WINFIELD SCOTT STEVENSON, OF ZANESVILLE, OHIO.

BUTT-WELDING PIPE.

Application filed October 10, 1923. Serial No. 667,728.

To all whom it may concern:

Be it known that I, WINFIELD SCOTT STEVENSON, a citizen of the United States, residing at Zanesville, in the county of Muskingum and State of Ohio, have invented certain new and useful Improvements in Butt-Welding Pipes, of which the following is a specification.

The present invention is directed to improvements in bells used for butt welding pipes.

The primary object of the invention is to provide a device of this character so constructed that the skelp can be drawn therethrough with very little effort, but at the same time the skelp will take a pipe form and its longitudinal edges will be firmly welded during the drawing operation.

A further object of the invention is to provide a device of this kind provided with a pair of aligned bearings of different size so that as the skelp is pulled through the bearings it will be acted upon by both bearings so as to effectively weld the longitudinal edges of the skelp to produce a section of pipe.

With these and other objects in view, as will appear as the description proceeds, the invention consists in the novel features of construction, combinations of elements and arrangements of parts, and hereinafter to be fully described and pointed out in the appended claims.

In the accompanying drawing:

Figure 1 is a longitudinal sectional view through the device, and

Figure 2 is a sectional view on line 2—2 of Figure 1.

The device comprises a pair of sections 1 and 2 the former having a bell shaped mouth 3 which opens into a longitudinal bearing 4, said mouth serving to bend the skelp 5 into initial pipe like form as the heated skelp is drawn thereinto in the usual manner.

The section 2 has a chamber 6 in its inner end which is aligned with the bearing 4 of the section 1, said chamber opening into a longitudinal bearing 7 of the section 2. This bearing is slightly less in diameter than the bearing 4 of the section 1 with which it aligns.

In order to unite the sections 1 and 2 and hold the same suitably spaced, the section 2 has its inner end provided with a plurality of bridge pieces 8, four of which are shown,

but it will be of course understood that the number may be varied if desired. These bridge pieces are provided with shoulders 9 and extensions 10. The extensions lap upon the adjacent end of the section 1 and at which time the rim of said section engages the seats 9. These extensions 10 are fixed to the section 1 so that the device will be a unitary structure and the sections rigidly united by the bridge pieces 8.

In operation the skelp 5 will be curled as it is pulled into the mouth 3 and will then take an initial pipe form as it passes through the bearing 4 and as the skelp is drawn into and through the bearing 7 the longitudinal edges thereof will be forced firmly into abutting relation and welded.

It will be obvious that as the skelp is drawn through the bearing 7 the proper reduction and elongation will be obtained with no more effort on the part of the workman than if it was pulled through the bearing only.

It sometimes occurs when using a single section or what is termed in the trade as a bell the skelp when too hot and drawn therethrough the bearing is cut and the pipe as well as the section is a loss. By arranging the sections 1 and 2 in tandem, should the bearing of the section 1 be cut the section would be a loss, but the skelp would be properly drawn into pipe form by the bearing 7 of the section 2, and while both sections are lost the pipe is completed and is usable.

Another advantage of having the bearing 7 in the section 2 smaller than the bearing 4 of the section 1 is that should the skelp be too wide for the bearing 4 it will be initially positioned so that its side edges will be brought into proper alignment and finally into a welding position as the skelp is successively drawn through the smaller bearings 7 and at which time the edges will be in such alignment as to prevent overlapping thereof, thereby assuring a perfect butt weld of the edges. By having the sections 1 and 2 arranged in tandem and varying the size of the bearings the draft and reduction of a skelp in forming a pipe will be normal to the pull, and with proper handling of the skelp approximately 75 per cent of the "bite off" and "tong slip off" will be eliminated.

By employing the bridge pieces the sections are held longitudinally spaced a sufficient distance to permit cinders to drop from the skelp before passing into the sec-

tion 2. This space, however, is of such size that the skelp will not cool after leaving the section 1 and before passing into the section 2 to such an extent as to prevent a perfect weld.

It will be observed that the bearings 4 and 7 are of substantially the same contour so that the skelp will be subjected to the same action as it is drawn from the section 1 into 10 the section 2.

What is claimed is:

1. A pipe forming bell comprising a forming section and a welding section, said sections being provided with longitudinally 15 aligned bearings, the bearing in the forming section being of greater diameter than the bearing in the welding section, and said welding section being provided at one end with a plurality of longitudinally extending 20 transversely spaced bridge extensions having recesses provided in the outer ends thereof for the reception of the end of the adjoining forming section, and the spaces between said bridge extensions being such 25 as to provide outlets at intervals around the full circumference of the bell.

2. A pipe forming bell comprising a forming section and a welding section, said sections being provided with longitudinally 30 aligned bearings, the bearing in the forming section being of greater diameter than

the bearing in the welding section, and one of said sections being provided with a plurality of longitudinally extending transversely spaced bridge extensions having recesses provided in the ends thereof for the reception of the complementary end of the adjoining section, the spaces between said bridges providing outlets at intervals around the full circumference of the bell. 35

3. A pipe forming bell comprising a primary forming section and a secondary welding section, said sections being provided with longitudinally spaced axially aligned bearings, the bearing in the secondary section 40 being of smaller diameter than the bearing in the primary section, and cinder outlets provided at intervals around the full circumference of said bell between said bearings.

4. A pipe forming bell comprising a primary forming section and a separable secondary welding section, said sections being provided with longitudinally spaced axially aligned bearings, the bearing in the secondary section being of smaller diameter 55 than the complementary bearing in the primary section, and a socket provided in the end of one of said sections for the reception of the adjoining end of the other of said sections.

In testimony whereof I affix my signature.
WINFIELD SCOTT STEVENSON.
